UNITED STATES PATENT OFFICE.

ARTIE L. CLINE, OF SPRINGDALE, ARKANSAS.

SAW.

1,137,838.

Specification of Letters Patent.

Patented May 4, 1915.

Application filed April 29, 1914. Serial No. 835,235.

To all whom it may concern:

Be it known that I, ARTIE L. CLINE, a citizen of the United States, residing at Springdale, in the county of Washington and State of Arkansas, have invented certain new and useful Improvements in Saws, of which the following is a specification, reference being had to the accompanying drawings.

10 This invention relates to certain improvements in saws and the object of the invention is to provide a device of this general character having novel and improved means whereby the same may be employed with convenience and facility as a bevel square.

15 The invention consists in the details of construction and in the combination and arrangement of the several parts whereby certain important advantages are attained and 20 the device is rendered simpler, less expensive and otherwise more convenient and advantageous for use, all as will be hereinafter more fully set forth.

25 The novel features of the invention will be carefully defined in the appended claim.

In order that my invention may be the better understood, I will now proceed to describe the same with reference to the accompanying drawings, wherein—

30 Figure 1 is an elevational view of a saw constructed in accordance with an embodiment of my invention; Fig. 2 is a sectional view taken substantially on the line 2—2 of Fig. 1; Fig. 3 is a view, partly in elevation and partly in section, of the saw handle herein set forth; and Fig. 4 is a sectional view taken substantially on the line 4—4 of Fig. 1.

35 As disclosed in the accompanying drawings, 1 denotes a saw blade having suitably secured thereto the handle 2, and it is to be observed that the inner edge 3 of the handle is at right angles to the back 4 of the blade 1 so that such inner edge 3 of the handle and back edge 4 of the saw may be employed as a square. It is also to be observed that the rear longitudinal marginal portion of the saw is provided with a lineal measure 5, for purposes which are believed to be clearly 45 obvious. As herein disclosed, the inner edge 3 of the handle 2 at opposite sides of the blade 1 has suitably affixed thereto, as herein disclosed, the metallic straps 6, the upper extremities whereof having hingedly 50 engaged therewith, as at 7, the rearwardly directed strap or flat arm 8 adapted to over-

lie the upper edge of the handle 2. Pivotally engaged, as at 9, with the under surface of the strap or arm 8 is the segment 10 depending within the kerf 11 of the saw 60 handle 2 and provided with the segmental slot 12 through which is projected the clamping screw 14 whereby it will be readily perceived that the strap or arm 8 may be adjusted at any desired angle and effectively maintained in such adjustment through the medium of the clamping screw or member 14. In order that the degree of angle of adjustment of the strap or arm 8 may be readily determined, I provide the 70 inner marginal portion of such segment 10 with the graduations 15, such graduations serving for a purpose and in a manner which is believed to be clearly obvious. In order that the clamping member or screw 14 may 75 be operated with convenience and facility, I provide the same with the winged head 16. The clamping screw or member 14 intermediate its length is provided with an annular groove or recess 17 in which the segment 10 80 is received and coacting with the inner extremity of the shank of the member 14 is a nut or bur 18 positioned within the recess or pocket 19, the walls of the pocket 19 maintaining the nut or bur 18 against axial rotation. It is also to be observed that the nut or bur 18 is of a thickness less than the depth of the pocket or recess 19 in order 85 that the nut or bur 18 may have the requisite clamping coaction with the segment 10. 90

From the foregoing description, it is thought to be obvious that a saw constructed in accordance with my invention is of an extremely simple and comparatively inexpensive nature and is particularly well 95 adapted for use by reason of the convenience and facility with which it may be assembled, and it will also be obvious that my invention is susceptible of some change and modification without material departure 100 from the principles and spirit thereof and for this reason I do not wish to be understood as limiting myself to the precise arrangement and formation of the several parts herein shown in carrying out my invention in practice. 105

I claim:

A measuring instrument comprising a blade and a handle, said handle being provided with a kerf to receive an extremity of 110 the blade, the back edge of the blade and the inner edge of the handle being perpen-

2
dicularly related, an arm pivotally engaged with the forward portion of the handle at a point substantially flush with the back edge of the blade, a segmental member pivotally secured to the arm and projecting within the kerf of the handle, said segmental member being provided with an arcuate slot, a clamping member rotatably supported by the handle and projecting through 10 the slot of the segmental member and in swivel engagement with said segmental member, the inner extremity of said clamping member being threaded, said handle being provided with a recess in communication

15 with the kerf thereof into which the threaded extremity of the clamping member projects, and a bur positioned within the recess of the handle in threaded engagement with the clamping member, the walls of the recess and the bur coacting to maintain said bur against axial rotation. 20

In testimony whereof I hereunto affix my signature in the presence of two witnesses.

ARTIE L. CLINE.
